[57] CLAIM

The ornamental design for a border edging, as shown and described.

DESCRIPTION

FIG. 1 is a perspective view of the border edging showing our new design, drawn on an enlarged scale from FIGS. 2-6; FIG. 2 is a front elevation view, the rear elevation view being a mirror image thereof;

FIG. 3 is a top plane view;

FIG. 4 is a right view;

FIG. 5 is a left view; and,

FIG. 6 is a bottom view.
